VENT AND AIR INLET ASSEMBLY

Marius W. Marrapese, Bedford, Ohio, and Edgar W. Wirth, New Athens, Ill., assignors to Autocrat Corporation, New Athens, Ill., a corporation of Illinois
Filed June 3, 1965, Ser. No. 460,928
4 Claims. (Cl. 98—62)

This invention relates to a vent and air inlet assembly and, more particularly, to a vent and air inlet assembly for furnaces.

The vent and air inlet assembly of the invention has particular utility when used with furnaces having a sealed combustion chamber in which primary air for combustion is obtained from outside the space being heated. These furnaces may draw primary air through an inlet passage which is carried through the same wall or ceiling aperture through which the flue passes to vent the products of combustion. For maximum safety and combustion efficiency the incoming primary air should be substantially entirely free of the exhausted combustion products. The flow of primary air should be principally governed by combustion chamber requirements and should be substantially free of gusts or surges of air resulting from climatic conditions prevailing at the primary air inlet. Water from rain, snow, etc., should be excluded from the furnace air inlet and exhaust since it could damage the furnace and possibly extinguish the furnace burner. Particular difficulty has been experienced in producing roof mounted vent and air inlet assemblies for mobile homes and travel trailers containing furnaces with sealed combustion chambers due to the long distance the primary air must be drawn into the combustion chamber and the fact that it is drawn "counterflow," i.e., opposite to the direction it tends to flow due to heating of the primary air.

Among the several objects of the invention may be noted the provision of a furnace vent and air inlet assembly in which passage of gases through the assembly is substantially immune to fluctuations in climatic conditions; the provision of a vent and air inlet assembly particularly adapted for use with a furnace having a sealed combustion chamber wherein the assembly prevents entrance of rain into the furnace even when the assembly is roof-mounted on the structure containing the furnace; the provision of a furnace vent and air inlet assembly wherein primary air entering the assembly is substantially free of exhaust gases discharged through the assembly; and the provision of a roof mounted vent and air inlet assembly for furnaces with a sealed combustion chamber wherein the assembly is capable of shielding the air inlet and exhaust outlet from the effects of wind and water without unduly impairing the required flow of air into the furnace and the exhaust of gases from the furnace. Other objects and features will be in part apparent and in part pointed out hereinafter.

The invention accordingly comprises the constructions hereinafter described, the scope of the invention being indicated in the following claims.

In the accompanying drawings, in which one of various possible embodiments of the invention is illustrated,

FIG. 1 is a section through a vent and air inlet assembly of this invention taken on line 1—1 of FIG. 2, the assembly being shown in connection with a furnace having a sealed combustion chamber;

FIG. 2 is an enlarged plan of the FIG. 1 vent and air inlet assembly;

FIG. 3 is an elevation of the FIG. 2 assembly; and

FIG. 4 is an exploded view of the assembly.

Corresponding reference characters indicate corresponding parts throughout the several views of the drawings.

2

Referring to the drawings, a vent and air inlet assembly 1 of the invention is shown in FIG. 1 mounted on the roof 3 of a structure containing a furnace generally designated 5. The furnace shown is of the sealed combustion chamber type in which primary air for combustion is drawn from outside the structure being heated. Furnace 5 has a combustion chamber 7 in which fuel is burned. The resulting products of combustion are exhausted through a vent or flue 9 communicating with the upper end of combustion chamber 7 and a flue 11 of the vent and air inlet assembly 1. Primary air for combustion is drawn through a passage 13 in assembly 1, travels between the sides 15 or back 17 of the furnace housing and an inner furnace wall 19, and then enters air inlets 21 in the lower part of the sides of the combustion chamber. The structure containing furnace 5 is heated by air from within the structure passing between inner furnace wall 19 and the front furnace wall 23 in heat exchange relation with combustion chamber 7. The upper and lower portions of front wall 23 have openings 25 and 27, respectively, through which interior air may enter and leave the furnace. The air to be heated may enter openings 27 and leave openings 25 due to convection currents resulting from heating within the furnace, or the air being heated may be circulated in the reverse direction by means of a furnace blower fan (not shown).

Surrounding and concentric with flue 11 is a collar 29 which receives a duct 31 (FIG. 1) communicating between assembly 1 and the air inlet to furnace 5. Primary air passage 13 is formed by flues 9 and 11, collar 29 and duct 31. The outer end of collar 29 constitutes the inlet end of the annular passage 13 and it communicates with the atmosphere through assembly 1. A stop 33 projects inwardly from the outer end of collar 29 to prevent projection of duct 31 above the outer end of collar 29.

An air passage cover 35 has a generally flat inner portion 37 sealingly engaging the periphery of an intermediate portion of flue 11. Portion 37 of cover 35 projects radially outwardly from flue 11 and an axially extending annular rim portion 39 of cover 35 depends from the periphery of center portion 37 and projects toward roof 3. Rim portion 39 of cover 35 is substantially coaxial with flue 11 and collar 29 and is positioned radially outwardly from collar 29.

Projecting radially outwardly from the inner end of collar 29 is a flange 41 for mounting assembly 1 on roof 3. Cover 35 is supported above flange 41 by generally Z-shaped brackets 43, ends 45 and 47 of the brackets being attached to flange 41 and cover 35, respectively.

A tubular deflector 49 is attached to an intermediate portion of brackets 43 and is spaced from both the inner portion 37 and rim 39 of cover 35 and from the mounting flange 41. Deflector 49 surrounds the outer end of collar 29 (thus surrounding the inlet to air passage 13) and it is positioned between the lower margin of rim portion 39 of cover 35 and the inlet end of air passage 13. Deflector 49 thus has an intermediate portion substantially in radial alignment with the inlet of air passage 13 so that atmospheric air traverses a tortuous path around the deflector between it and cover 35 or flange 41 before it enters the air passage.

Deflector 49 has an annular series of spaced ports 50 axially located beneath the lower edge of cover 35 and substantially in radial alignment with the outer end of collar 29. Located between the collar 29 and deflector 49 is a tubular deflector 51. Deflector 51 is spaced axially from mounting flange 41 and the annular center portion 37 of cover 35. Deflection 51 is supported above mounting flange 41 by angle brackets 52. The top of deflector 51 is slightly lower than deflector

49 and its lower end is in substantially the same plane as the bottom of deflector 49. Deflector 51 is positioned between ports 50 and the inlet of air passage 13 so that air passing through ports 50 and beneath deflector 49 must pass either beneath deflector 51 or over the deflector 51 and beneath cover 35 before it can enter the air passage. Deflectors 49 and 51 are both substantially coaxial with flue 11 and collar 29.

The solid arrows in FIGS. 1 and 3 show the paths available for primary air through the assembly between the atmosphere and the passage 13. One path is beneath the lower edge of rim portion 39 of cover 35, then above the deflector 49 and above deflector 51 into the inlet end of passage 13. A second path is beneath deflector 49, then above deflector 51 and into passage 13. A third path is through the ports 50 and then above deflector 51 into the passage 13. A fourth path is beneath deflector 49 (or through holes 50), beneath deflector 51 and then over the end of collar 29 and into passage 13. In each instance the air must traverse a tortuous path through the air inlet portion of assembly 1 before entering passage 13. This substantially prevents gusts of air sweeping across roof 3 from directly entering the air inlet passage and thus upsetting the natural draw or pull of furnace 5 for primary air. The deflectors and cover arranged as shown also act as a splash guard and prevent ingress of rain water, snow, etc., into the furnace through the air inlet assembly.

The outer end of flue 11 projects above cover 35 and is surrounded by another tubular deflector 55. Deflector 55 is substantially coaxial with flue 11 and is the same diameter as deflector 51. Deflector 55 is supported above and spaced from the center portion 37 of cover 35 by brackets 57 attached to the deflector and the cover. The outlet of flue 11 is in radial alignment with an intermediate portion of deflector 55.

A flue cover 59 has a circular center portion 61 and an annular rim portion 63 and an annular rim portion 63 depending from the periphery of center portion 61. Cover 59 is mounted above cover 35 by braces 65 attached to the rim portions of both covers. Deflector 55 is located between the lower margin of the rim portion 63 of cover 59 and the outer end of flue 11 so that products of combustion from furnace 5 discharged through flue 11 traverse a tortuous path as they escape the assembly. Center portion 61 of cover 59 is spaced from the upper margin of deflector 55 so that the flue and gases may pass either above or beneath deflector 55 and then between covers 35 and 59 to the atmosphere. These paths are shown by the dashed arrows in FIGS. 1 and 3. Cover 59 and deflector 55 also prevent entrance of water into the outlet end of the flue 11 and prevent gusts of wind from blowing into the outlet end of flue 11 thereby opposing discharge of the combustion products.

In use, mounting flange 41 is attached to roof 3 of a structure containing furnace 5. Flue 11 of assembly 1 projects into a hole cut in roof 3 to accommodate the assembly. Flue 11 receives and accommodates furnace flue 9. Collar 29 receives duct 31 for communicating primary air inlet passage 13 with the furnace 5.

Assuming the furnace 5 is operating and that combustion is taking place in chamber 7, primary air is drawn into the inlets 21 of the combustion chamber, thereby pulling primary air through the assembly 1. As the air passes through assembly 1 it must pass beneath cover 35 and pass above, below or through deflector 49, and then above or below deflector 51, and finally over the outer end of collar 29 to enter the passage 13. It is then drawn through the furnace 5 between inner wall 21 and the side walls 15 or back wall 17 of the furnace.

The furnace combustion products are discharged from chamber 7 into flue 9 and then through flue 11 of assembly 1. The combustion products then pass either above or below deflector 55 and between covers 59 and 35 to the atmosphere. Rim 39 of cover 35 provides a distinct separation

between exhaust gases and incoming primary air, thus preventing any significant portion of the exhaust gases from mixing with atmospheric air entering the assembly. As a result, the incoming primary air is more suitable for combustion of fuel in chamber 7 than if it contained large portions of exhaust gases previously discharged through flue 11.

The adverse effects of gusts of wind entering either the air inlet passage 13 or the flue 11 are avoided by the arrangement of the covers and deflectors positioned beneath them. Thus the flow of primary air into the furnace is governed almost entirely by the combustion chamber requirements and is substantially free of gusts or surges of air. Since the primary air surrounds flues 9 and 11 and is cooler than the exhaust gases, it insulates roof 3 from the heat of the exhaust gases. Moreover, rain water droplets, snow, etc. are excluded from both the air inlet and flue of the assembly, thereby preventing water damage to the furnace.

Due to the elimination of the adverse effects of air variations caused by climatic conditions (as opposed to furnace requirements) the vent structure of the invention is suitable for use on mobile homes and travel trailers where the primary air must be pulled a greater than normal distance into the furnace and where this movement of primary air is "counter-flow" (i.e., opposite to the direction the primary air tends to flow by convection due to heating of this primary air by combustion products passing through flues 9 and 11). Vents mounted on the walls of mobile homes do not require any substantial counterflow of air and the air is usually pulled a much shorter distance than for roof mounted vents. Moreover, in wall mounted vents there are no special difficulties in excluding rain, etc. Thus the wall mounted vent and air inlet assemblies do not have to overcome the particular problems roof mounted vents encounter. For this reason wall mounted vents are not suitable for roof mounting. The vent and air inlet assembly of the invention, on the other hand, may be mounted on a wall of a structure as well as on the roof.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

What is claimed is:

1. A vent and air inlet assembly for a sealed combustion chamber gas furnace, the assembly being mountable on the exterior of a structure containing the furnace and comprising an elongate flue for exhausting combustion products from the furnace combustion chamber to the atmosphere, an elongate conduit surrounding and spaced from the flue, the conduit being coaxial with the flue and defining with the flue a passage for primary air for the furnace combustion chamber with the outer end of the conduit comprising the inlet of the passage, the outer end of the flue projecting beyond the outer end of the conduit, an air passage cover engaging the periphery of the flue and overlying but spaced from the outer end of the conduit, the cover having an annular rim depending from its periphery, a first tubular deflector surrounding the inlet end of the passage and positioned between the inlet end of the passage and the rim of the cover, the cover rim being coaxial with and spaced from the conduit, means supporting the deflector in spaced relation to the exterior of the structure and the cover with an intermediate portion of the deflector being in radial alignment with the inlet of the passage whereby atmospheric air traverses a tortuous path beneath the cover and around the deflector before entering the air passage, a second tubular deflector supported above the cover and surrounding the

outlet end of the flue, a second cover overlying and spaced from the outer end of the flue, the second deflector being spaced from the flue and both covers, the first deflector including a series of ports, the deflector ports being substantially in radial alignment with the inlet end of the passage, and a third tubular deflector located between and spaced from the first tubular deflector and the conduit.

2. A vent and air inlet assembly for a sealed combustion chamber gas furnace, the assembly being mountable on the exterior of a structure containing the furnace and comprising an elongate flue for exhausting combustion products from the furnace combustion chamber to the atmosphere, an elongate conduit surrounding and spaced from the flue, the conduit being coaxial with the flue and defining with the flue a passage for primary air for the furnace combustion chamber with the outer end of the conduit comprising the inlet of the passage, the outer end of the flue projecting beyond the outer end of the conduit, an air passage cover engaging the periphery of the flue and overlying but spaced from the outer end of the conduit, the cover having an annular rim depending from its periphery, a first tubular deflector surrounding the inlet end of the passage and positioned between the inlet end of the passage and the rim of the cover, the cover rim being coaxial with and spaced from the conduit, means supporting the deflector in spaced relation to the exterior of the structure and the cover whereby atmospheric air traverses a tortuous path beneath the cover and around the deflector before entering the air passage, a second tubular deflector supported above the cover and surrounding the outlet end of the flue, a second cover overlying and spaced from the outer end of the flue, the second deflector being spaced from the flue and both covers, the first deflector including a series of ports, the deflector ports being substantially in radial alignment with the inlet end of the passage, and a third tubular deflector located between and spaced from the first tubular deflector and the conduit, the third deflector being spaced from the first cover and axially positioned between the ports in the first deflector and the inlet end of the passage whereby air entering the ports is deflected by the third deflector before it enters the passage.

3. A vent and air inlet assembly as set forth in claim 2 further including a mounting flange surrounding the conduit for mounting the assembly on the exterior of the structure, the lower end of the third deflector being spaced from the flange throughout the circumference of the deflector whereby air passing around the first deflector or through its ports must pass either between the third deflector and the first cover or beneath the third deflector before entering the passage.

4. A vent and air inlet assembly for a sealed combustion chamber gas furnace, the assembly being mountable on the roof of the structure containing the furnace and comprising a tubular flue adapted to communicate through

its lower inlet end with the exhaust of the furnace combustion chamber and pass products of combustion through its outer outlet end to the atmosphere, a tubular conduit surrounding the lower portion of the flue and defining with the flue an annular air passage for primary air, the lower end of the air passage constituting its outlet end and adapted to communicate with the furnace combustion chamber air inlet, the upper end of the conduit constituting the air passage inlet end and communicating with the atmosphere through the assembly, the outer end of the flue projecting beyond the outer end of the conduit, an air passage cover in sealing engagement with the periphery of the flue above the inlet end of the air passage, the cover having an annular inner portion extending radially outwardly from the flue and an axially extending annular rim portion at its periphery, a tubular deflector surrounding the conduit and positioned between the lower margin of the rim portion of the cover and the inlet end of the air passage, the deflector being spaced from the cover and the roof of the structure and having an intermediate portion in radial alignment with the inlet end of the air passage whereby atmospheric air traverses a tortuous path around the deflector between the cover and roof before entering the air passage, a second cover supported above the first cover, the second cover having a circular center portion overlying the outlet end of the flue and having an annular rim depending from the periphery of its center portion, a second tubular deflector positioned between the lower margin of the rim portion of the second cover and the outlet end of the flue, the second deflector being spaced from the flue and both covers whereby furnace combustion products discharged through the flue traverse a tortuous path around the second deflector in escaping the assembly, the second cover and second deflector shielding the outlet end of the flue from the entrance of droplets of water, and a third tubular deflector positioned between the inlet end of the air passage and the first deflector, the third deflector and the first cover defining a path for air passing through the assembly into the air passage.
